UNITED STATES PATENT OFFICE.

THOMAS MOONEY, OF DOUGLASTON, NEW YORK.

LIQUID DOOR-CHECK.

1,123,780.

Specification of Letters Patent.

Patented Jan. 5, 1915.

Application filed August 21, 1912. Serial No. 716,181.

To all whom it may concern:

Be it known that I, THOMAS MOONEY, a citizen of the United States of America, residing in Douglaston, county of Queens, 5 Long Island, State of New York, have invented a certain new and useful Liquid Door-Check, of which the following is a specification.

This invention relates to liquid door 10 checks of that class adapted to be set in the sill of the door to act on the lower part of the door, and embodies a structure capable of closing a double acting door.

As illustrated in the accompanying drawings: Figure 1 is a longitudinal vertical section, showing some of the parts in elevation. Fig. 2 is a plan view with the covers of the casing removed. Fig. 3 is a transverse vertical section on the line A, B Fig. 20 2, and Figs. 4 and 5 are vertical sections of the cylinder and piston, detached, showing only so much thereof as to illustrate the relation of these parts to one another.

The casing 1 is closed by the cover plates 25 2 and 3, the cover 2 being readily removed for the inspection of the working parts with the device in operative position. The cover plate 3 is provided with a bearing in alignment with a bearing 5 in the bottom of the 30 casing at one of its ends; these bearings hold a vertical shaft 4 which is fastened to the door axially in line with its swinging axis, and the means for such connection may be a bar 8 adapted to be secured to the 35 lower edge of the door and attached to the shaft 4 by a square 7 on its upper end fitting into a corresponding hole in the bar. The casing is provided with horizontal bearings 13 and 14 which hold a shaft 12 operatively 40 connected to shaft 7 by bevel wheels 10 and 11. Walls or partitions 13' connect the bearing 13 to the side walls of the casing, forming a pocket for holding a lubricant into which the gear 11 will extend and which 45 reaches the lower end of the shaft 4, resting on a step washer 6, through a slot 4' in the side of the bearing 5.

The shaft 12 between the bearings 13 and 50 14 carries two motor springs 15 and 16 whose inner ends connect with sleeves provided with notched heads or flanges 17, 18, and their outer ends are held by hooked lugs 23, 24 formed on the side walls of the casing. The heads are locked to the shaft 55 12 by dogs or pawls 20 on rods passing through holes formed through the shaft,

said dogs being securely held in the notches 19 of the heads 20, in which they may be set, by springs 21 held on the rods by lock nuts 22. This arrangement of the springs 60 15, 16 is such that they tend to turn the shaft 12 in opposite directions, they are adjusted to counterbalance and hold the door in closed position, one being strengthened by being further wound up when the door is 65 moved in one direction and the other one strengthened by being further wound up when the door is moved in the other direction. On the other end of the shaft 12 which carries the bevel gear 11 is secured 70 an arm 25 provided with a crank pin 26, carrying a connecting rod 27 whose lower end by pin 28 controls the action of the piston 29. This piston is fitted to vertically reciprocate in a cylinder 30 formed integral 75 with the casing 1, and below the cylinder is provided a pressure chamber 31. Extending from the top of the cylinder are grooves 32 constituting ports whose lower ends are uncovered when the piston is in its highest 80 position, as shown at Fig. 3. The upper part of the piston is cup shaped and through the side are formed openings 33 which align with the ports 32 and register with them during a portion of the piston's stroke. 85 Extending through the bottom of the piston are passages 34, 35 having enlarged chambers at their lower ends in which ball valves 36, 37 are held by a clip 42. These ball valves close the lower ends of the passages when at the upper ends of their chambers.

A by-pass is provided between the pressure chamber 31 and the cylinder and casing consisting of passages 38, 39 and 40, the 95 flow of the liquid through them being governed by a valve on the end of a rod 41 located over the upper end of the passage 38, said valve rod being screw threaded, whereby close and fine adjustment of the flow of 100 liquid through the by-pass may be made.

A suitable liquid, as a mixture of glycerin, 105 alcohol and water, is applied in the casing so as to entirely fill the pressure chamber 31 and partly fill the casing to a point above the cylinder. The lower edge of the piston is above the lower ends of the ports 32 of the cylinder when the piston is in its uppermost position, and as the piston in descending cuts off the flow of the liquid from the chamber 31 through the ports it is 110 advantageous that such cut-off shall not be

sudden, and to avoid this the lower part of the piston may be tapered or beveled as shown at Figs. 3 and 4, or the lower ends of the ports 32 may be inclined downwardly, as shown at 32' Fig. 5. Either method will avoid sudden shocks by providing for a gradual cutting off of the flow and insure an easy change in the speed of the door occurring at this time. With the door closed the piston is in its lowermost position, shown at Fig. 1. As the door is opened in either direction the piston rises and the liquid flows down the passages 34, 35 and by-pass offering little resistance to the movement of the door, but before the piston rises to its highest position the ports 32 are opened, as shown at Fig. 3, which shows the position of the parts with the energy of the spring 16 increased, when the door has been moved in a right-hand direction looking toward its pivotal connection. No resistance to the action of the spring is offered when the door is released until the door is closed to an extent for the piston to close the ports 32, which causes sufficient pressure in the chamber 31 to force the ball valves 36, 37 to their seats, leaving the by-pass passage as the only exit from the chamber 31 for the liquid and the speed of movement of the door is further decreased until it is within a few degrees of closing, and then the pressure in chamber 31 will have dropped sufficiently to allow the valves 36, 37 to fall away from their seats, allowing the piston to descend freely and removing practically all resistance to the final closing of the door.

Of course it will be readily understood that checks embodying the essential features of this device may be used to control doors opening only one way; one drive spring then only will be needed.

I claim:

1. A double acting door check including a casing, a vertical shaft mounted in the casing, connections between the door and said shaft whereby the door may be swung in either direction, a horizontal shaft in mechanical connection with the vertical shaft, and checking appliances adapted to operate upon the horizontal shaft.

2. A double acting door check including a casing, a vertical shaft mounted in the casing, connections between the door and said shaft whereby the door may be swung in either direction, a horizontal shaft in mechanical connection with the vertical shaft, opposed spring devices and a liquid checking device, the said spring and checking devices being adapted to operate upon the horizontal shaft.

3. A double acting door check including a casing, a vertical shaft mounted in the casing with its axis coinciding with the axis of the door, connections between the door and

said shaft whereby the door may be rotated in either direction by the shaft, a horizontal shaft in mechanical connection with the vertical shaft, and checking appliances adapted to operate upon the horizontal shaft.

4. A liquid floor door check comprising a spring actuated shaft, means connecting the door and the shaft for rotating the shaft when the door is moved, a cylinder having grooved ports extending downwardly in its inner wall, a piston fitted to reciprocate in the cylinder having its upper part cup-shaped or recessed and having openings through its wall arranged to register with the ports of the cylinder, and means connecting the piston to the spring actuated shaft.

5. In a liquid door check, a casing, a shaft, a spring to actuate the shaft, connections between the door and the shaft for rotating the shaft when the door is moved, a cylinder located in the casing, the cylinder having a uniform bore and being equipped with grooved ports extending longitudinally along its inner wall, a tapered piston, and connections between the piston and said shaft whereby the piston may be reciprocated in the cylinder.

6. In a double-acting door check in combination, a vertical shaft, means connecting it to the door coincident with the axis of movement of the door, a horizontal shaft connected to rotate with the vertical shaft, two springs adjustably connected to the horizontal shaft with their directions of action opposed and to hold the door closed, and a liquid controlled means actuated from the horizontal shaft.

7. In a double-acting door check in combination, a vertical shaft, means connecting it to the door coincident with the axis of movement of the door, a horizontal shaft connected to rotate with the vertical shaft, two springs adjustably connected to the horizontal shaft with their directions of action opposed and to hold the door closed, a cylinder, a piston operating therein and actuated by the horizontal shaft, and a pressure chamber beneath the cylinder and piston.

8. In a double-acting door check in combination, a vertical shaft, means connecting it to the door coincident with the axis of movement of the door, a horizontal shaft connected to rotate with the vertical shaft, two springs adjustably connected to the horizontal shaft with their directions of action opposed and to hold the door closed, a cylinder having internally longitudinally arranged ports, a piston operating therein and actuated by the horizontal shaft, to open and close the cylinder ports at their lower ends, and a pressure chamber beneath the cylinder and piston.

9. In a double-acting door check in com-

bination, a vertical shaft, means connecting it to the door coincident with the axis of movement of the door, a horizontal shaft connected to rotate with the vertical shaft, 5 two springs adjustably connected to the horizontal shaft with their directions of action opposed and to hold the door closed, a cylinder having internally longitudinally arranged ports, a piston operating therein 10 and actuated by the horizontal shaft to open and close the cylinder ports at their lower ends, and a pressure chamber beneath the

cylinder and piston, valve controlled passages extending through the piston to the pressure chamber, and a by-pass with an adjusting valve connecting the interior of the cylinder and the pressure chamber. 15

In testimony whereof, I have hereunto subscribed my name.

THOMAS MOONEY.
